PREDETERMINED COUNTER

Warren H. Bliss, Princeton, N. J., assignor to
 Radio Corporation of America, a corporation of
 Delaware

Application March 21, 1947, Serial No. 736,214

3 Claims. (Cl. 235—92)

1

This invention relates to control systems such as are adopted (1) to limit industrial processes to a selected interval of time, (2) to control a device for delivering a selected number of articles to be enclosed in a container, (3) to control or vary the relation between the frequencies of an input and an output potential, or (4) to exert a control effect generally in cases where it is desired to count or measure quantities such as periods of time, numbers of objects or the like.

In many processes such as spot welding and chemical reactions it is desirable to have available a stop watch type of apparatus which may be utilized to terminate the process at the end of a pre-determined time interval or to measure the time required for the completion of such processes. In other processes such as the bottling or packaging of articles, it is desirable to provide means whereby selected numbers of such articles may be automatically delivered to the containers in which they are to be sold. To avoid wear and waste of energy, and to attain high operating speeds it is sometimes desirable that the counting and measuring apparatus be automatically reset to its standby condition or cease to operate at each completion of the controlled process.

In accordance with the present invention, these results are achieved by means of a control system which includes a plurality of trigger circuits connected in groups of four each of which (1) is arranged to complete its cycle of operation in response to ten input pulses, and (2) is provided with means whereby any count of the group may be selected for the purpose of exerting a control effect. These different groups or decades are connected in tandem so that one control pulse is delivered from a higher speed decade to the next lower speed decade each time such higher speed decade completes its cycle of ten counts. Thus if 0.01 second is required to complete the cycle of the first or higher speed decade, the cycle of the second decade will be completed in 0.1 second, that of the third decade in 1 second, etc.

The trigger circuit of which the decades are constituted may be of different types. It is illustrated as including a pair of triodes each of which (1) has its anode coupled to the grid of the other through a resistor shunted by a capacitor, (2) has its cathode grounded, (3) has bias potential applied to its grid through a separate resistor, and (4) has operating potential applied to its anode through a separate resistor and a resistor which is common to the anodes of both triodes.

With these connections, only one of the triodes

conduct current at a time. Current conduction is transferred from one to the other of the triodes in response (1) to the application of a negative pulse to the grid of a triode which is conducting, (2) to the application of a positive pulse to the grid of a triode which is not conducting or (3) to the application of a negative pulse to the lead through which the separate anode resistors are connected to the common anode resistor. In all cases, the pulses to be counted are applied to the input of the highest speed decade which represents the lower orders of the entire count.

The selector for producing a desired control effect in response to different numbers of pulses applied to the input of the highest speed or lowest order decade is illustrated as a three point switch which is moved over three series of fixed contacts which are each connected to a different anode of the decade through a resistor. These connections between the decade anodes and the fixed contacts of the switch are so arranged that the switch delivers a positive control potential only in response to a number of decade input pulses determined by the setting of the switch.

The output terminals of the selector switches of the various decades are connected to a control circuit which functions to deliver a control potential only in response to the number of decade input or counting pulses which is determined by the setting of the selector switches of the different decades. In the illustrated form of the invention, this control potential is utilized to reset the various decades to their standby condition and to produce some effect in a circuit external to the control system itself. Obviously it may be utilized to terminate the supply of input pulses to the highest speed decade if desired and to produce various other effects.

The principal object of the invention is the provision of an improved control system and method of operation whereby a control pulse is reproduced in response to any desired number of input pulses. An important object of the invention is the provision of an improved control system which includes a minimum of parts and is simply operated to limit an operation or effect to any selected time interval. Another object is the provision of an improved control system which is adapted to respond to a selected number of input pulses after which it is automatically reset to its standby or zero count condition.

The invention will be better understood from the following description considered in connection with the accompanying drawing and its scope

55 is indicated by the appended claims.

The single figure of the drawing is a wiring diagram of the improved control circuit. It shows in its lower section a four decade counter, the first decade of which is shown in detail and the other decades of which are shown as boxes. At the upper left-hand section of the figure is shown the details of the selector switch for the first decade. The selector switches of the other decades are shown as boxes located above the corresponding decades. The control circuit to which all these selector switches are connected is shown at the upper mid-section of the figure. The output lead of the control circuit is connected to an output lead and a reset circuit shown at the upper right-hand section of the figure.

Input pulses are applied to the first decade through a coupling capacitor 10. This decade includes four trigger circuits V1 to V4 which are connected in tandem through coupling capacitors 26, 27 and 28. Operating potential is applied to the anodes of the trigger circuits V1 to V4 respectively through common anode resistors 20 to 23. The anodes of the different trigger circuits are indicated respectively by the reference numerals 11 and 12, 13 and 14, 15 and 16 and 17 and 18. It will be noted that (1) the anode 15 of the trigger circuit V3 is coupled through a capacitor 62 and a resistor 63 to the right-hand grid of the trigger circuit V2 and (2) the anode 17 of the trigger circuit V4 is coupled through a capacitor 60 and a resistor 61 to the right-hand grid of the trigger circuit V3. In the zero count or standby condition of the decade, current conduction is in the right-hand triode of each trigger circuit as indicated by arrows adjacent the separate anode resistors.

The operating cycle of the decade is indicated by the following tabulation:

Pulse	V1	V2	V3	V4
0	R	R	R	R
1	L	R	R	R
2	R	L	R	R
3	L	L	R	R
4	R	R	L	R
5	L	L	L	R
6	R	R	R	L
7	L	R	L	L
8	R	L	L	L
9	L	L	L	L
10	R	R	R	R

In this tabulation, the number of applied input pulses is indicated by the numerals of the first column, the letter R indicates that current conduction is in the right triode of the trigger circuit, and the letter L indicates that current conduction is in the left triode of the trigger circuit. It will be noted that after the fourth input pulse V2 is turned back left when V3 turns left and that V3 is similarly turned left when V4 turns left.

The anodes 11 to 18 of the decade are connected respectively through resistors 70 to 77 to the fixed contacts of a selector switch S1. Movable contacts 78, 79 and 80 are arranged so that each moves along a different row of these fixed contacts. By comparing the arrangement of the fixed contacts with the above tabulation, it is easy to see that the most positive pulse is applied to the output lead 81 of the switch S1 only when the number of input pulses applied to the decade corresponds to the switch position indicated by the numerals at the left-hand side of the fixed contacts.

Thus if the movable contacts 78 to 80 are in

the "4" position, for example, the switch output lead 81 is connected to the anodes 11, 16 and 17. As shown by the tabulation, all these anodes are not conducting and are at a relatively high positive potential at the count of 4. In the same way, the lead 81 is made more positive at the proper count for any other setting of the switch S1.

The decade V1 to V4 has its output coupled through a capacitor 82 to a similar decade 83. Subsequent decades 84 and 85 are similarly connected in tandem with the first two stages through capacitors 86 and 87. Additional decades may be likewise connected through a capacitor 88.

15 The selector switch S2 is connected through a lead 89 to the output lead 81 of the selector S1 and thence to the control grid of a pentode 90. The selector switches S3 and S4 of the decades 84 and 85 are connected through leads 91 and 92 and a common lead 93 to the control grid of a pentode 94.

Operating potential is applied from a lead 95 respectively through resistors 96 and 97 to the anodes 98 and 99 of the pentodes 90 and 94.

25 When a more positive potential is applied from all the selector switches S1 to S4 to the grids of the pentodes 90 and 94, current is drawn through the resistors 96 and 97 and the potentials of the anodes 98 and 99 is made more negative. These 30 anodes are connected to ground through separate resistors 100 and 101 and a common resistor 102 so that such more negative potential of the anodes is applied through a resistor 103 to the control grid of a pentode 104. Capacitors 105 and 106 may be connected in shunt to the resistors 100 and 101 for increasing the speed of operation.

When the grid potential of the pentode 104 is made more negative, less current is drawn through its anode resistor 107 and a positive pulse is applied to the output lead 108, and to the input lead 109 of the circuit by which the various decades are reset to their zero or standby condition.

40 45 The reset circuit includes a gas tetrode 110 which derives its operating potential from a lead 111 through a resistor 112. The cathode and control grid of the tetrode 110 are connected respectively through a resistor 113 and a resistor 50 114 to a negative lead 115 through which bias potential is applied to the various grids of the decades.

Connected between the anode and cathode of the tetrode 110 in series with the output load 55 resistor 113 is a capacitor 116 which is charged during the normal non-conducting state of the tetrode 110. When the previously mentioned positive pulse is applied to the grid of the tetrode 110 through the lead 109, the tetrode becomes 60 conductive and the capacitor is discharged through the load resistor 113. As a result, a positive pulse is applied to the reset lead 117 of the various decades which are thereby put into their standby condition.

65 70 For normally setting the bias potentials applied to the decade grids a resistor 118 may be connected in the lead 115 as indicated.

If desired the control circuit including pentodes 90, 94 and 104 may be somewhat simplified (1) by reversing the two leads from each trigger circuit to the selector, (2) by providing the pentodes 90 and 94 with a common anode resistor and maintaining them normally at saturation anode current, and (3) by omitting the pentode 104.

75 Under these conditions, the pentodes are driven to

cutoff in response to the selected count and a positive pulse is applied from their common anode lead resistor to the leads 108 and 109.

What the invention provides is a control system which is readily adjusted to respond to any desired number of input pulses for producing a control effect and which is automatically restored to its normal standby condition when such effect has been produced.

I claim as my invention:

1. The combination of a plurality of decade counters connected in tandem and each including a plurality of trigger circuits of which each includes a pair of triode elements each having a grid, a cathode, and an anode, each of said pairs of triode elements having their grids and anodes cross-connected so that current is conducted either by one or the other of said triodes, means for applying input pulses to the lowest order decade of said plurality of decades, means for selectively deriving from the anodes of said triodes a control pulse which is of the same polarity and value for any number of said input pulses within the counting range of said decades, a reset lead for said decades, an electron discharge device having grid, cathode and anode electrodes, said reset lead being coupled to said discharge device to derive an output therefrom, a capacitor coupled between said electron discharge device anode and cathode, and means to impress said control pulse upon said electron discharge device to discharge said capacitor through said discharge device whereby said decades are reset in their standby conditions.

2. The combination of a plurality of decade counters connected in tandem and each including a plurality of trigger circuits of which each includes a pair of triode elements each having a grid, a cathode, and an anode, each of said pairs of triode elements having their grids and anodes cross-connected so that current is conducted either by one or the other of said triodes, means for applying input pulses to the lowest order decade of said plurality of decades, means for selectively deriving from the anodes of said triodes a control pulse which is of the same polarity and value for any number of said input pulses within the counting range of said decades, a reset lead for said decades, an electron discharge device having grid, cathode and anode electrodes, an output load for said discharge device coupled to said cathode, said reset lead being connected to said cathode to derive an output therefrom, a capacitor connected across said electron dis-

charge device and said output load, and means for applying said control pulse to the control grid of said electron discharge device to discharge said capacitor through said impedance to provide a reset pulse across said output load.

3. The combination of a plurality of decade counters connected in tandem and each including a plurality of trigger circuits of which each includes a pair of triode elements each having a grid, a cathode, and an anode, each of said pairs of triode elements having their grids and anodes cross-connected so that current is conducted either by one or the other of said triodes, means for applying input pulses to the lowest order decade of said plurality of decades, means including three-point switches each having fixed contacts connected to all the anodes of a different one of said decades for selectively deriving a control pulse which is of the same polarity and value for any number of said input pulses within the counting range of said decades, a reset lead for said decades, a gas electron discharge device having anode, cathode and grid electrodes, a capacitor, a resistor having one end connected to said cathode, said reset lead being connected to said cathode to derive an output therefrom, said condenser being connected between said discharge device anode and the other end of said resistor, and means to impress said control pulse upon said discharge device grid to render said discharge device conductive to discharge said condenser through said discharge device and to reset said decades to their standby conditions.
